(57) **CLAIM**

The ornamental design for a self-retaining nasal septum retractor, as shown and described.

DESCRIPTION

FIG. 1 is a perspective view of a self-retaining nasal septum retractor showing my new design;

FIG. 2 is a front elevational view thereof;

FIG. 3 is a rear elevational view thereof;

FIG. 4 is a top view thereof;

FIG. 5 is a right side elevational view;

FIG. 6 is a left side elevational view; and

FIG. 7 is a bottom view thereof; and,

FIG. 8 is a perspective view with the arm hinges angled downwards.

The broken lines are directed to the environment and are for illustrative purposes only; the broken lines form no part of the claimed design.
